UNITED STATES PATENT OFFICE

163,325

GAME BOARD

Robert L. Robbins, Jr., Berkeley, Calif., assignor
to Gordon L. Byers, Berkeley, Calif., as trustee

Application November 20, 1950, Serial No. 13,060

Term of patent 3½ years
(Cl. D34—5)

To all whom it may concern:

Be it known that I, Robert L. Robbins, Jr., a citizen of the United States, residing at Berkeley, in the county of Alameda, and State of California, have invented a new, original, and ornamental Design for a Game Board, of which the following is a specification, reference being had to the accompanying drawings, forming part thereof.

Figure 1 is a top plan view of the game board showing my new design;

Figure 2 is an enlarged fragmentary showing on the central portion of the board; and

Figures 3 to 10, inclusive, are enlarged fragmentary disclosures of the corners thereof.

The game board is shaded to indicate color contrast. The board is of conventional thickness.

I claim:

The ornamental design for a game board, as shown and described.

ROBERT L. ROBBINS, JR.
